UNITED STATES PATENT OFFICE.

MICHAEL LANG, OF LOS ANGELES, CALIFORNIA.

CABINET.

1,191,710.

Specification of Letters Patent. Patented July 18, 1916.

Application filed February 23, 1915. Serial No. 10,133.

To all whom it may concern:

Be it known that I, MICHAEL LANG, a citizen of the United States, residing at Los Angeles, in the county of Los Angeles and

5 State of California, have invented a certain new and useful Improvement in Cabinets, of which the following is a specification.

10 My invention relates to a cabinet for talking machine records, and has especial reference to a mechanism for projecting the records in order to enable their convenient removal. In most cabinets, as constructed today, which contain some arrangement for moving the record for a certain distance out 15 of the cabinet to afford a hold for the user, a separate and distinct element or combination of elements for each individual record is employed.

20 An object of my invention, therefore, is to provide a cabinet in which a single means for all records is used in projecting them individually out of the cabinet.

25 Other objects will appear from the subjoined specification in connection with the accompanying drawing, in which—

Figure 1 is an elevation of a cabinet showing my invention as applied. Fig. 2 is a section on line 2—2 Fig. 6. Fig. 3 is a perspective view showing the operating bar with its 30 locking key in engagement with the notched plate. Fig. 4 is an end view of the lever. Fig. 5 is a section on lines 5—5 Fig. 4, and Fig. 6 is an enlarged section on lines 6—6 Fig. 1.

35 Referring to the drawing, 1 designates a cabinet, having a plurality of walls 2, forming partitions which divide the cabinet into compartments for talking machine records 3.

Pivotedly hung from a support 4 is a lever 40 5, the end of which extends in the rear of and below the center of a record, as seen in Fig. 4, and is provided on each side with a wing 6, forming substantially a U, for enabling said end to take a firm hold on and

45 prevent it from slipping engagement with the record. Approximately intermediate and pivotally connected at one end with said lever 5, is a link 7, having its other end pivotally attached to a bar 8, that is pivotally connected to a carriage 9, and to which carriage is secured the support 4 for the lever 5.

50 On the other end of said bar 8 is a weight 8' for holding the lever 5 in and returning the same to normal position, as will appear hereinafter. This carriage 9 is provided with a plurality of rollers 10, running

in a track 11 extending transversely through the cabinet, and is connected with a carrier 12, by a tube 13, through which extends a rod 14, having a bent end 15, loosely connected with said lever 5 by a pin 16. The other end of said rod 14 is provided with a knob or button 17, by which the rod may be pulled outwardly to effect the operation of the lever 5 and consequently the movement 65 of a record. Said carrier 12 is provided with a plurality of wheels 18, arranged to run on a track 19, whereby to shift the entire mechanism heretofore described, and bring the lever 5 in position for projecting a desired 70 record.

In order to prevent the movement of the carrier 12 and its connected parts while the rod 14 is in withdrawn position, as indicated in dotted lines Fig. 6, the rod 14 is provided 75 with a key 20, for engagement in the notches 21, of a strip 22, in front of said carrier 12. When a certain record is desired to be taken from the cabinet, the carrier 12, by means of the button 17, is moved along the track 80 19, until the indicator 23 on the carrier 12 points to the desired one of the circles 23' on the front of the cabinet, in which circles may be inscribed the titles or numbers of the records. The rod 14 is then pulled outwardly, causing the lever 5 to project the record, and the weighted bar 8 to be lifted, as shown in dotted lines, Fig. 6. When in withdrawn position, the key 20 of the rod 14 is in engagement with one of the notches 90 21 of the strip 22, such engagement preventing the lateral movement of the rod. The lever 5, as seen in Figs. 4 and 5, may be bent upon itself to form substantially a U, the base of which may be provided with slots 24, 95 25 and 26, through which extend the bar 8, rod 14, and link 7, respectively, whereby the lever is held rigidly in a vertical position.

What I claim is:

1. In a record cabinet, a lever in operative 100 position to the rear of a record, a track, a carriage movable on said track, a support on said carriage for said lever, a weighted bar pivotally connected to said carriage, a link connecting said lever and bar, a carrier, 105 a track on which said carrier runs, a tube connecting said carriage and carrier, and a rod extending through said tube and operatively connected with said lever.

2. In a record cabinet, a lever in operative 110 relation to the rear of a record, a track, a carriage movable on said track, a support

on said carriage for said lever, a bar pivotally connected to said carriage means connecting said bar to said lever, means on said bar to hold said lever in normal position, a carrier, a track on which said carrier runs, a tube connecting said carriage and carrier, a rod extending through said tube and operatively connected with said lever to operate the same, and means to lock said rod against movement laterally when in operative position.

3. In a record cabinet, a lever in operative relation to the rear of a record, a rod connected with said lever and operable to eject a record, a carriage for said rod movable laterally to position said lever with respect to a desired record, a notched bar on said cabinet, and a means on said rod for en-

gagement with the notches in said bar to prevent lateral movement of said rod when withdrawn.

4. In a record cabinet, a lever in operative position to the rear of a record, a support for said lever, a rod operatively connected with said lever to eject a record, a support for said rod movable laterally to position said lever with respect to a desired record, a notched bar on said cabinet, and a key on said rod to engage the notches in said bar simultaneously with the operation of said rod.

In testimony whereof I have set my hand in the presence of two witnesses.

MICHAEL LANG.
